Specification of Letters Patent. Patented June 30, 1914.

Application filed September 18, 1905. Serial No. 273,901.

To all whom it may concern:

Be it known that we, ALEXANDER E. KEITH, JOHN ERICKSON, and CHARLES J. ERICKSON, citizens of the United States of America, 5 and residents of Chicago, Cook county, Illinois, have invented a certain new and useful Improvement in Automatic Telephone Systems, of which the following is a specification.

- 10 Our invention relates to calling devices for use in automatic telephone systems and more particularly in systems in which electrically-propelled and step-by-step-actuated switching machines are employed, as, for 15 example, the well-known "individual-switches", "selectors" and "connectors" employed in automatic telephone systems for enabling a calling subscriber to establish the desired connection with the called subscriber's line, without the assistance of a switchboard operator, or for at least accomplishing one or more of the connective operations usually performed by switchboard operators.
- 20
- 25 Heretofore, as is well known, the rotatable dial or wheel, employed in many automatic systems, and constituting the calling device by which one subscriber calls the number of another subscriber, has been of such character that its forward rotation by the subscriber produces no make-and-break action in the line-circuits, and consequently produces no impulses during its forward rotation and the consequent winding up of the 30 spring by which it is returned to its normal position; but when it is released by the calling subscriber, and allowed to return to its normal position, under the influence of its spring, a certain number of impulses are 35 then transmitted over one side of the line, according to the character of the digit being called, and the degree of rotation given the dial or wheel; and when these successive impulses have been transmitted over the so-called vertical side of the subscriber's line—that is to say, that side of the line over which the impulses are transmitted for giving any switching machine a vertical step-by-step motion of its switch-shaft—a single impulse

is then transmitted over the so-called rotary-line-conductor for the purpose of effecting the automatic rotation of a "selector-switch" until it finds an idle trunk-line, or for the purpose of putting the mechanism of a "connector-switch" in such condition that 55 the next group of impulses transmitted over the vertical-line-conductor will produce the desired step-by-step rotation of the "connector-switch-shaft" until the particular line of the called subscriber is found and 60 connection made therewith. With this arrangement, it is evident that the so-called "individual-switch" is operated by the first impulse produced by the rotatable dial or wheel when it is released by the calling subscriber for the first time, and as soon as it starts to return to its normal position, this impulse being also the ordinary or regular initial impulse employed for giving the switch-shaft of the "first-selector" its initial 70 or first vertical step. In this way, the calling subscriber does not cause the operation of any switching machine—either an "individual-switch" or a "first-selector"—until he releases his calling device for the first 75 time, and the return of the dial or apertured wheel to its normal position is then accompanied by what is very nearly a simultaneous operation of the "individual-switch" and the "first-selector", although it is evident that the first vertical step of the "first-selector" cannot take place until after the "individual-switch" has automatically established connection with the idle trunk-line extending to such "selector".

The objects of our invention are to provide an improved arrangement and construction of the calling devices by which the subscribers produce the electrical impulses or rapid make-and-break effects corresponding to the several digits of any called subscriber's number; to provide an improved construction and arrangement whereby the forward rotation of the dial or subscriber's calling device produces a single 90 long impulse or closure of a grounded circuit including one side of the subscriber's line, which single impulse produced by the

forward rotation of the subscriber's dial is capable of producing the desired automatic selection of an idle or non-busy trunk-line, through the medium of an "individual switch," and also the first vertical step of the "first-selector" or other switching machine with which the "individual-switch" has connected the calling subscriber's line; to provide an improved construction and arrangement whereby the forward rotation of a subscriber's dial or calling device produces the first vertical step of a "selector" or other switching machine, and whereby the release of such dial, and its consequent return to its normal position, produces a series of impulses of a character suitable for operating automatic selector and connector switches; to provide an improved construction and arrangement for governing the return movement of the dial or subscriber's calling device, so as to insure against a too rapid back rotation or return movement of the same, and so as to insure a proper transmission of the electrical impulses; to provide an improved construction and arrangement for governing the depression or return of the subscriber's hook-switch to its normal position, when the subscriber replaces his receiver upon the said hook, and for thus insuring a proper transmission of the electrical impulse or impulses by which the switching machinery at the central station is released or restored automatically, so to speak, by the hanging up of the calling subscriber's receiver; and to provide certain details of construction and various other features of improvement tending to increase the general efficiency, serviceability and certainty of operation of an automatic telephone system.

In the accompanying drawings, Figure 1 is a diagrammatic view of the substation circuits. Fig. 2 is a front elevation of a subscriber's hook-switch and calling device involving the principles of our invention, the dial or rotatable apertured wheel being shown in dotted lines. Fig. 3 is a side elevation of the mechanism shown in Fig. 2, certain portions being broken away for convenience of illustration. Fig. 4 is an enlarged perspective of the inner portion of the switch-hook. Fig. 5 is a detail sectional view of the governor for controlling the return movement of the switch-hook and dial. Fig. 6 is an end view of the said governing device, with certain portions removed. Fig. 7 is a detail sectional view showing the pivotal mountings for the switch-hook. Fig. 8 is a rear elevation of the mechanism shown in Fig. 2. Fig. 9 is a view similar to Fig. 8, but showing the switch-hook in its depressed or normal position, rather than in the raised position in which it is shown in Figs. 2 to 8. Fig. 10 is a detail view of certain parts

shown in Figs. 8 and 9, showing said parts 65 in the positions given them by the initial rotation of the dial after the removal of the receiver from the switch-hook. Fig. 11 is a perspective of the three integrally-formed switch-operating fingers which are 70 mounted upon and operated by the switch-hook. Fig. 12 is a detail sectional view showing the construction of the ground-circuit-controlling-arm which is secured to the shaft or axis of the dial. Fig. 13 is a section on line 13—13 in Fig. 3. Fig. 14 is a fragmentary perspective view of a portion of the electrical impulse-transmitting mechanism. Fig. 15 is a perspective of the two impulse-springs. Figs. 16 to 21, inclusive, 80 show the said impulse-springs of the subscriber's calling mechanism, and illustrate different positions thereof relatively to the toothed wheel and the grounded contact.

Fig. 1 shows diagrammatically the circuits and apparatus at the substation connected to the line conductors c^{28} and c^{29} , which are assumed to extend to a central station and there terminate in a suitable "individual" switch. These circuits and 90 apparatus will be more readily understood when considered in connection with the remaining drawings, which show the apparatus in detail.

The construction of the subscribers' hook-switches and calling devices, to which our invention relates, is as follows: Referring to Figs. 2 to 21, inclusive, it will be seen that the framework comprises a front plate 1 and a back plate 8, the two being rigidly 100 connected together by the three rods 2. Upon this framework all of the operative parts of the calling and switch-hook mechanisms are mounted in a suitable manner. The shaft 7 extends centrally through the 105 said plates 1 and 8, and is arranged to rotate freely in its bearings thereon. A dial or apertured wheel 3 is rigidly secured to the front end of this shaft, as shown in dotted lines in Fig. 2 and in full lines in Fig. 3. It 110 will be understood that the said dial can be secured to the end of the shaft in any suitable or desired manner. Near the periphery of the dial there are, as will be observed, a series of openings—ten in number—said openings being numbered consecutively in any suitable or desired manner. Directly behind the said dial 3, as shown in the drawings, there is a clock-spring 4. This spring is secured at one end to a projection on the front plate at the point 4^a, and is held circumferentially by the projecting arms 4^b. The inner end of this spring is fastened to the shaft 7 in such manner that its tension, when it is wound, 120 gives it a tendency to rotate the shaft in such a direction as to carry the apertures in the dial in a counter-clockwise direction

from the positions in which they are shown in Fig. 2, for example. Mounted upon this shaft 7 there is also a gear-wheel 48 arranged to revolve freely on the shaft at all times except when engaged by ratchet-arms, as will hereinafter more fully appear. In addition, the toothed disk or impulse-wheel 12 is fastened to the shaft by means of the clamp 14. The arm 43 is also rigidly secured to said shaft. A receiver-hook 33 is pivoted at the point 49, and is arranged to have a limited up and down movement when the receiver is removed and replaced. It will be seen that this receiver-arm has an extension rigidly secured to it and to which is pivoted a piece or dog 34 at the point 39. This dog 34 is, it will be seen, engaged by a spring 34^a which normally holds it in contact with the teeth of the ratchet-wheel 48. Furthermore, this dog is so arranged that the hook will, when the receiver is removed therefrom, move freely over the teeth of the gear-wheel 48, without engaging these teeth; but when the receiver is hung upon the hook, the dog is then drawn into contact with the teeth of the gear-wheel 48, and as the hook moves down to its normal or depressed position, the gear-wheel is thereby caused to revolve with it; but when the hook has ceased its downward motion, the said gear-wheel may then continue to revolve, owing to the momentum which has been given it, as the position of its spring will allow the dog to move freely over the teeth of the gear-wheel as it continues its rotation. The hook and the dog 34 are shown in detail in Fig. 4, and the method of pivoting the hook between the plates 1 and 8 is shown in Fig. 7. A release-cam 21 is shown in perspective in Fig. 11. Details of the construction are shown in Fig. 16, and the parts are shown assembled on the frame or body in Figs. 3, 8 and 9. The release-cam 21 is fastened rigidly to the hook at the point 21^a. At its upper extremity, the cam 21 is provided with a piece of insulation 21^a. Near its central portion, it is also provided with an arm having a lateral projection 21^b, and at its lower end it is provided with another arm having the projection 21^c. When the telephone receiver rests upon the hook, the latter being down, as shown in Fig. 9, the arm 21^a then rests upon the so-called ringing-circuit-spring 28, causing the contacts of the springs 26, 28 and 29 to be brought to the positions shown in Fig. 9. When the receiver is removed from the hook, this arm 21^a is then disengaged from the ringer-spring 28, allowing the contacts of springs 26, 28 and 29 to be raised, as shown in Fig. 8. The arm 46 is pivoted to the receiver-hook at 46^a, its extremity being engaged by the spring 11, which latter is rigidly secured to the por-

tion 42. The tension of this spring tends always to keep the receiver-hook in an elevated position—that is, when the receiver is not in place upon the hook. As the hook moves in an upward direction, the arm 21^b passes by the front side of a projection allotted to the release-springs 23, 24 and 25—the projection being at the end of the spring 25—thus at this time keeping the said springs entirely separated; but as this hook moves back to its normal or depressed position, the finger 21^b then reengages this projection on its back side, thereby forcing the springs 23, 24 and 25 momentarily together, and thus producing the release operation of the calling device. As the hook moves to its raised position, the arm with the insulation 21^a engages the projecting finger 20^a of the locking-arm 20, thereby revolving it around a point 20^b, the latter being its pivotal point. This arm 20 carries a bushing 20^c. When in its normal position, the said arm 20 engages the screw 43^c of the arm 43, thus locking the dial in such condition that it is impossible to turn the same until the receiver is removed from the hook. It will be understood, of course, that the swinging or revolving motion about the point 20^b is only for a comparatively short distance, and that the bushing 20^c is preferably of some suitable insulating material.

As the hook rises, the insulation 21^a engages the portion 20^a, as already stated, and thereby raises the arm 20 out of locking position. Also, as the portion 21^a moves out of contact with the ground-spring 19, this spring is thereby allowed to rest against the insulation 20^c. This, it will be seen, is the position of the spring 19 until the first partial rotation of the dial occurs—that is to say, the first partial rotation made by the calling subscriber in order to send impulses corresponding to the first digit of the called subscriber's number, it being necessary to partially rotate the dial and then release it and allow it to return to its normal position in order to accomplish the desired make-and-break action in the grounded line-circuit, resulting in the transmission of electrical impulses corresponding to the first digit of the called number; and when this is done, the pin 43^c of the arm 43 strikes against the lower edge of the locking-arm 20, thus raising it sufficiently to allow the elbow in the end of the spring 19 to slip under the bushing 20^c. This, of course, allows the spring 19 to make contact with the arm 18^a; said spring 19 being ordinarily known as a ground-spring, and the finger 18^a as a ground-post. As the hook moves to its depressed position, the bushing 21^a again lifts the spring 19 out of contact with the portion 18^a. Also, when the spring 19 is lifted out of engagement with the bushing

20°, the arm 20 then moves back to its normal position, inasmuch as it is then actuated by its spring 40. After this, the arm 20 once more performs the function of locking the dial against movement when the receiver is on the hook. The detail construction of this locking device is shown fully in Fig. 12. The projecting finger 43^a of the arm 43 rests, when the dial is in its normal position, against the spring 30 of the talking-springs, thus holding it so that when the receiver is removed from the hook, the spring 29 will immediately make contact with such spring; but when the dial is moved forward, the portion 43^a is then disengaged from the spring 30, thus permitting the latter to break contact with the spring 29. Secured to the impulse-wheel 12 of the calling device, there is a dog 35 which is held normally in contact with the teeth of the gear-wheel 48, and which operates in a manner similar to the dog 34 attached to the receiver-hook—that is to say, as the dial rotates in a forward direction, this dog 35 passes freely over the teeth of the gear-wheel 48; but as the dial begins to rotate in a backward direction, in order to recover its normal position, and to control the backward speed of the dial, under the tension of the spring, this dog then engages the gear-wheel 48, causing the latter to revolve in unison. This, of course, actuates the centrifugal governor, which latter, however, will be described farther on in connection with other matters. The said gear-wheel is, as will be observed, caused to revolve or rotate when the hook is moved downward, or when the dial is moved by the tension of the clock-spring. The teeth of this gear-wheel engages with the teeth of a pinion 9, this being shown in Figs. 2, 3, 8 and 9, and the pinion being shown in cross-section in Fig. 5, and in end elevation in Fig. 6. It may be stated at this juncture that this pinion is a part of the so-called governor or governing device—that is, the device which controls the speed of the dial when it rotates in a backward direction, and the speed of the switch-hook when the latter is returned to its normal position. Upon the end of the pinion are pivoted the two parts 32^a and 32^b which, taken together, form a circle, the part 32^a being pivoted at the point 32^a, and the part 32^b being pivoted at the point 32^b. These are held normally together, the circle being completed by means of the springs 32^b. These two parts are formed as shown in cross-section in Fig. 5, and are adapted to fit loosely upon the cup-shaped ring 32^c, which latter is rigidly fastened to the frame of the calling device. Now, as this pinion 9 revolves quite rapidly, when actuated by the gear-wheel 48, the ends of the parts 32^a

and 32^b farthest away from the respective pivots 32^a and 32^b fly out or away from the axis of rotation, and thus to a certain extent revolve about their respective pivots 32^a and 32^b. This, of course, will cause a binding of these parts against the stationary cup-shaped ring 32^c, producing sufficient friction to reduce the speed of the gear-wheel 48, in case the rotation becomes too fast. The impulse-wheel 12, which is rigidly secured to the shaft 7, carries the arm 13 having a single projecting tooth. Mounted upon the frame of the calling device, and rigidly fastened to it, there is a vertical impulse-spring 15, and also a rotary impulse-spring 17, the same being so placed or disposed that they will come in contact with the teeth of the impulse-wheel. These springs are shown more clearly in Figs. 1, 16 and 21, the shape of these springs being shown more clearly in Figs. 14 and 15. The so-called vertical impulse-spring 15 is composed of the two parts 15^a and 15^b, the part 15^a being so arranged that, as it moves away from the spring 15, the said spring 15 will tend to follow it, while if moved in the opposite direction, against the spring 15, it will then cause the latter to move with it.

Obviously, as the dial is moved forward by the calling subscriber, the positions then occupied by the vertical teeth are shown in Figs. 18 and 19, the tendency of spring 15 being to rest against the contact 18. For this reason, and when the dial is moved forward and the projection 12^a of the impulse-wheel is moved into contact with the projecting portion 15^a, the spring 15 then moves into contact with the portion 18, and as the wheel continues to revolve, each successive tooth 12^b, 12^c, etc., engages the front portion of the spring 15^b, thus holding the spring 15 in contact with the arm 18, and giving it the one long vertical impulse. This impulse, produced by a temporary grounding of the vertical side of the calling subscriber's line, lasts the full length of time required to move the dial forward to the desired number on the face of the dial. Now, as the dial begins to rotate back to its normal position, under the tension of the dial-spring, the position of the spring 15 is as shown in Fig. 20—that is to say, the tooth 12^c engages the outer part of the spring 15^b, thus forcing the spring 15 out of contact with the arm 18; and it will remain in this position until the spring 15^b drops over the tooth 12^c, when it will then again make a momentary contact with the ground-arm 18; and then, as the dial continues to rotate, the spring 15 will again be forced out of contact with the portion 18, by the tooth 12^b, and so on by the other teeth in succession, giving the required num-

ber of impulses in rapid succession. Immediately after the last vertical impulse is made, the spring 17 then moves into contact with a single tooth on the arm 13, thus forcing it against the ground-arm 18, and thus giving the single impulse over the rotary-line-conductor—that is, the single impulse which always follows a group of impulses transmitted over the vertical-line-conductor for the purpose of performing an operation corresponding to one digit of the called number. The position of the so-called vertical spring at this juncture is shown in Fig. 21. Fig. 17 shows the position of the so-called rotary spring at the time the dial is again to rotate in a forward direction under the manual force exerted by the calling subscriber. Fig. 18 is a cross-section taken on a line just at the left of the impulse-wheel 12 shown in Fig. 3. As illustrated, a fiber portion 50 is fastened to the frame for convenience in carrying the wires or flexible conductors. Also, with the construction set forth, a clip 41 is fastened to the frame, thereby permitting electrical connection to be made between the wiring and the frame of the calling device.

It will thus be seen that we have devised a very efficient form of calling device which is normally locked against rotation and in which the initial or forward operation of the dial produces a prolonged impulse over one side of the line and the return movement of the dial produces a plurality of impulses over one side of the line followed by a single impulse over the opposite side of the line.

While we have illustrated and described one specific embodiment of our invention, it will, of course, be understood that we do not wish to limit ourselves to this exact construction, as various changes and modifications will be readily suggested to those skilled in the art.

45 What we claim as our invention is:

1. A telephone system comprising a subscriber's calling device or electrical impulse-transmitting mechanism including a rotatable dial and a normally-open ground-switch, said dial being adapted by its forward rotation to temporarily close the said ground-switch, and adapted by its return rotation to again close the said ground-switch.

55 2. A telephone system comprising a subscriber's calling device including a rotatable dial and a normally-open switch, said dial being adapted by its forward rotation to temporarily close the switch, and adapted by its return rotation to again close the switch.

60 3. A telephone system comprising a subscriber's combined hook-switch and calling

mechanism, said mechanism comprising a rotatable dial adapted by its forward rotation to transmit an electrical impulse, and by its return rotation to transmit one or more additional impulses, centrifugal governing mechanism for controlling the return movements of both the dial and the switch-hook.

4. A combined hook-switch and calling mechanism comprising a rotatable dial and normally-open switch, said dial being adapted by its forward rotation to temporarily close said switch, and by its return rotation to again close the switch, and centrifugal governing mechanism for controlling the return movements of both the dial and the hook-switch.

5. A subscriber's mechanism for calling the number of any other subscriber, comprising a rotatable member and means whereby such member is adapted by its forward rotation to transmit an electrical impulse substantially equal in duration to the forward rotation given the member and adapted by its return rotation to transmit either none or one or more relatively short electrical impulses, according to the degree of rotation given the dial.

6. In a telephone system, an impulse transmitter including a calling dial adapted to be operated forward a variable distance and then returned to normal position, and a pair of normally separated contacts adapted to be closed during the forward movement of said dial and then momentarily closed a plurality of times, depending upon the extent of movement of said dial, during the return of said dial to normal position.

7. In a telephone system, an impulse transmitting device including a ground connection, a pair of normally open spring contacts for controlling said ground connection, a switch hook for normally locking said transmitter against operation, means controlled by the upward movement of said switch hook for unlocking said transmitter, means controlled by the initial operation of said transmitter for closing said contact springs and ground connection, and means controlled by the subsequent operation of said transmitter for intermittently operating said contact springs.

8. In a telephone system, an impulse transmitting device including a rotary calling dial, a ground connection, a pair of normally open contacts controlling said connection, a switch hook normally locking said calling dial against rotation, means operated by the upward movement of said switch hook for unlocking said dial, means controlled by the forward movement of said dial for closing said contact springs and said ground connection, and means controlled by

the subsequent operation of said transmitter for intermittently operating said contact springs.

9. In a telephone system, an impulse transmitter including a calling dial adapted to be operated in a forward direction a variable distance and then returned to normal position, and a pair of normally separated contacts adapted to be closed for a comparatively long period during the forward movement of said dial and then momentarily

closed a plurality of times, depending upon the extent of movement of said dial, during the return of said dial to normal position.

Signed by us at Chicago, Cook county, 15 Illinois, this 6th day of September, 1905.
